CLAIM

The ornamental design for a vortex generator for wind turbines, as shown and described.

DESCRIPTION

First Embodiment

FIG. 1 is a perspective view of a vortex generator for wind turbines that bears the design in accordance with a first embodiment.

FIG. 2 is a front view of the vortex generator of FIG. 1.
FIG. 3 is a back view of the vortex generator of FIG. 1.
FIG. 4 is a right side view of the vortex generator of FIG. 1.
A left side view of the vortex generator is a mirror image of FIG. 4.

FIG. 5 is a top view of the vortex generator of FIG. 1.
FIG. 6 is a bottom view of the vortex generator of FIG. 1.
Second Embodiment

FIG. 7 is a perspective view of a vortex generator for wind turbines that bears the design in accordance with a second embodiment.

FIG. 8 is a front view of the vortex generator of FIG. 7.
FIG. 9 is a back view of the vortex generator of FIG. 7.
FIG. 10 is a right side view of the vortex generator of FIG. 7.
A left side view of the vortex generator is a mirror image of FIG. 10.

FIG. 11 is a top view of the vortex generator of FIG. 7; and,
FIG. 12 is a bottom view of the vortex generator of FIG. 7.

(Continued)

The first and second embodiments are associated with a vortex generator where a pair of fins is disposed on a circular base plate.
